UNITED STATES PATENT OFFICE.

EMIL G. SAUER, OF BROOKLYN, NEW YORK, ASSIGNOR TO THE LOWELL MANUFACTURING COMPANY, OF MASSACHUSETTS.

DESIGN FOR CARPET.

SPECIFICATION forming part of Design No. 26,816, dated March 23, 1897.

Application filed February 2, 1897. Serial No. 621,702. Term of patent 3½ years.

To all whom it may concern:

Be it known that I, EMIL G. SAUER, a citizen of the United States, and a resident of Brooklyn, county of Kings, and State of New York, have invented a new Design for Carpets and Borders, of which the following is a specification.

This invention comprises two parts, namely, the design A for a carpet and the design B for a border; and I do hereby declare that the drawing accompanying this specification conveys to any one a clear understanding of the same and is sufficient to enable such person to use my invention.

15 The design A is characterized by small closely-associated figures of nondescript pattern extending over the entire face of the carpet.

The design B is characterized by a band

along its inner margin of small closely-associated figures and by a row of larger figures spaced at intervals along its outer margin.

What I claim as new, and desire to secure by Design Letters Patent, is—

1. In the design for a carpet, the body A, substantially as shown.
2. In the design for a carpet, the border B, substantially as shown.
3. The design for a carpet consisting of the body A, and the border B, substantially as shown.

In testimony whereof I have signed my name to this specification in the presence of two subscribing witnesses.

EMIL G. SAUER.
